UNITED STATES PATENT OFFICE.

JOSEPH G. THATFORD, OF SHARON HILL, PENNSYLVANIA.

PROCESS OF MANUFACTURING PLASTERERS' TROWELS.

1,015,654.

Specification of Letters Patent.

Patented Jan. 23, 1912.

Application filed July 19, 1910. Serial No. 572,698.

To all whom it may concern:

Be it known that I, JOSEPH G. THATFORD, a citizen of the United States, residing in Sharon Hill, county of Delaware, State of Pennsylvania, have invented certain Improvements in Processes of Manufacturing Plasterers' Trowels, of which the following is a specification.

My invention relates to certain improvements in the manufacture of plasterers' trowels.

It has been the usual practice heretofore to make the blade of plasterers' trowels separate from the shank and tang section. Efforts have been made to make the tang on which the handle is fitted in a single piece with the blade, but trowels of this type have not been produced commercially. Prior attempts to make a trowel with an integral shank and tang were failures, owing to the fact that the blade was first forged and reduced to the finished thinness prior to the slitting and bending of the projection to form the shank and tang, and it was also impossible to give the shank and the rib of the plate the form desired, owing to the fact that the extreme thinness of the blade would not permit the parts to be heated to the required degree, and any effort to forge, roll, or alter the form of the central rib would, in practice deform the extremely thin blade.

The object of my invention is to make the shank and tang portion integral with the blade of the trowel by a process in which the portion from which the tang and shank are formed is bent up and partly formed prior to the completion of the rolling or forging of the blade.

In the accompanying drawings,—Figure 1, is a perspective view of a plasterer's trowel illustrating my invention; Fig. 2, is a perspective view of the blank from which the trowel is formed; Fig. 3, is a perspective view showing the rib of the blank cut to form the tang portion; Fig. 4, is a view showing the tang portion bent into a position at right angles to the blade and partly formed; Fig. 5, is a view showing the blade rolled to the thickness required; Fig. 6, is a perspective view showing the shank and tang completed and the blade of the trowel reduced to the proper thickness.

While I have illustrated my invention in a plasterer's trowel of a certain size and shape, it will be understood that the invention can be applied to the various forms of

trowels, without departing from the essential features of the invention.

Referring in the first instance to Fig. 1, A is the blade of the trowel; B is the shank projecting from the back of the blade and shaped in any manner desired. In the present instance, as illustrated in Fig. 1, the shank is wide and narrow, being greater in width at the center b and tapered slightly 60 toward the point where it joins the blade, and also where it joins the tang b'. The handle C is driven on the tang. On the blade A is a longitudinal rib a, and in this instance, this rib extends substantially the 65 full length of the blade and acts to stiffen it. The rib illustrated in Fig. 1, is narrow and is beveled at the end, but it will be understood that the rib may be of any shape desired and may terminate any distance from 70 the shank, as it will be understood that plasterers' trowels vary in different localities. Some plasterers want trowels with stiff and heavy blades, others wish very light blades and different forms of shanks and handles, 75 and these slight variations can be made without departing from the main features of the invention.

In Fig. 2, I have illustrated a blank D, from which the trowel is made. This blank 80 is made by rolling or forging and has a heavy rib d projecting from one surface. The blank is cut from a bar, and in proper lengths to form trowels. The rib is of such a height that the shank and tang can be 85 formed from it. The first operation is to indent the rib on each side, as at e, Fig. 3, from one end to substantially the point where it is desired to have the shank project from the blade. These indentures extend 90 half way through the rib from each side, so as to meet at the center, and thus the portion d' is severed from the portion d'', and this portion d'' forms the rib at the 95 back of the blade. The portion d''' is cut 100 entirely away, as shown in Fig. 3, and discarded. If a rib is not desired, then I form the incisions e as near the blade as possible, so that when the blade is rolled or forged the rib is obliterated. The next step in the 105 process is to bend the portion d' of the rib away from the blade, preferably to a position at right angles to the blade, as illustrated in Fig. 4, and from this portion is formed the shank B. This portion is then 110 slightly reduced at f—f to prepare it for the final shaping described hereafter. The

- web or body portion of the blank is next reduced to the required thinness to form the blade of the trowel. This reduction can be made by rolling, forging or pressing, as desired, but I preferably roll one half and then the other half in two heats, the rolls being so shaped as to avoid the projecting shank B and to reduce the rib to the form desired. After the blade has been reduced 5 it is trimmed, as illustrated in Fig. 5, and the shank and tang are finished, the tang being bent to a position substantially at right angles to the shank and substantially parallel to the blade, as illustrated in Fig. 10 6. The blade is finally finished by being ground and polished in the ordinary manner.
- From the above description it will be seen 15 that I can accurately and economically make a plasterer's trowel in which the shank and tang are integral with the blade and the rib can be made of any shape and size desired, and I can also form the blade without the central rib, if desired.
- 20 25 The great objection to the trowels made in the ordinary manner, that is by riveting the ribbed handle portion to the blade, is that the blade is often torn from the handle portion, or the rivets become loose, thus 30 weakening the blade. The blade is in many instances bent, so that its working surface is not true, and it is almost impossible to get the blade back to its original true position.
- 35 In some instances, instead of forming the shank and tang integrally from a portion of the rib, I may form a portion of the latter into a shank element, which may be

considerably less in height than the portion necessary for a complete shank and tang, 40 and finish such shank element for the application of a separate tang, or a shank member carrying the usual tang to which the handle is secured; such separate tang, or shank member with tang, being attached to 45 the shank element formed up from the rib by any welding operation suited for the purpose, electrical or otherwise.

I claim:—

1. The process herein described of manufacturing plasterers' trowels, said process consisting in forming a blank with a rib projecting from one surface, cutting away a portion of the rib to form the shank, and then reducing the body portion of the blank 55 to form the blade of the trowel.

2. The process herein described of manufacturing plasterers' trowels, said process consisting in forming a blank with a rib on one surface thereof, cutting away a portion 60 of the rib at one end of the blank, leaving a central connection with the body portion of the blank, cutting the rib entirely away on the other side of the blank, bending that portion of the rib which remains integral 65 with the blank, then reducing the body portion of the blank to form the blade, and finally shaping the cut away portion of the rib to form the shank.

In testimony whereof, I have signed my 70 name to this specification, in the presence of two subscribing witnesses.

JOSEPH G. THATFORD.
